APPARATUS FOR CONVEYING PULVERULENT, BROKEN, OR LIKE MATERIALS

George Harry Strain, Seaford, England

Application July 9, 1940, Serial No. 344,598
In Great Britain August 8, 1939

13 Claims. (Cl. 198—220)

My U. S. Patent No. 2,192,668 describes and claims screening apparatus which comprises a rigid member or anvil, means for imparting to the rigid member a reciprocating motion having a vertical component, and a screen mounted on the rigid member in such a manner that it is normally held in, or nearly in, contact with the rigid member by the force of one or more springs or their equivalent, but is free to move against such force away from the position of contact.

The present invention is based on the observation that a machine for conveying pulverulent, broken or like material is obtained if a tray is mounted alongside the rigid member in the aforesaid manner and the rigid member is given a reciprocating motion having a component parallel to the direction in which the material is to be conveyed, this arrangement enabling the momenta of the apparatus to be substantially equal to the momenta of the impact, thus rendering extraneous vibrations either non-existent or negligible.

The action of the machine is similar to that described in U. S. Patent No. 2,192,668; the anvil carries the tray with it in one stroke, and on the return stroke the tray lags behind the anvil and is struck by the returning anvil at or near its point of maximum velocity, the momenta of anvil and tray substantially destroying one another. At each impact the material on the tray is advanced by a certain distance, and is thus gradually conveyed.

The term "tray" as used herein includes screens and other devices having a surface such that the material resting thereon can advance relatively thereto when the tray is subject to the impacts of the anvil.

The tray may be plane or of any other desired shape which permits the material to advance over its surface, and may be horizontal or inclined. If the tray slopes downwards in the direction of advance of the material the speed of advance will be increased and the material will be somewhat separated at each impact from the tray, returning to the latter under the action of gravity. The latter effect is of advantage in screening the material, the tray being in this instance a screen. If the tray slopes upwards in the direction of advance of the material, the advance will be retarded, but the material can still be conveyed even if the angle of inclination of the tray approaches the angle of repose of the material.

The tray may be mounted on the anvil by coil or leaf springs. If the rigidity of the springs to bending in the vertical plane is insufficient to

support the tray the latter may be further supported by struts and ties which permit it to move freely with and away from the anvil in a substantially horizontal plane. The struts and ties may be used for adjusting the inclination of the tray.

The invention is illustrated by way of example in the accompanying drawings, in which—

Fig. 1 is a vertical section, and

Fig. 2 is a plan partly in section of a machine according to the invention.

A tray 1 is mounted alongside an anvil 2 by means of coil springs 3 fixed at one end to the anvil and at the other to bolts 4 passing through a plate 5 which is bolted to struts 6 pivoted on the fixed members 7. The tray is pivotally attached to the struts 6 by means of bolts 8 which pass through perforations in angle plates 9 riveted to the screen and through bearings 10 in the struts 6. The bolts 4 are held in position by wing-nuts 11 which enable the periodicity of the springs 3 to be adjusted at will while the machine is in motion.

The anvil 2 is connected by connecting rods 12 with an eccentric 13 which causes the anvil to reciprocate at a frequency of, say, 1000 cycles per minute and at an amplitude of the order of a millimetre. The ends of the connecting rods 12 remote from the eccentric 13 are pivotally mounted by bolts 14 in bearings in struts 15 which are themselves pivotally mounted on the member 7.

Supporting the end of the tray 1 remote from the anvil 2 are rods 16 pivotally attached to the angle plates 9 and to bolts 17 which may be screwed up or down in order to vary the inclination of the tray and thus the speed at which the material is conveyed.

Impact plates 18 are fixed to the struts 6 and, as described above, strike the anvil 2 once in every oscillation. The plates 18 and anvil 2 are provided with rubber pads 19 to reduce the shock of the impact.

The material to be conveyed is fed to the tray 1 from a hopper 20 and at each impact is advanced towards the right as seen in the drawings. The tray is provided with wings 21 which sprinkle the material in a wide, shallow stream to a deflecting plate 22 which delivers the material to any desired position.

The invention overcomes the difficulty experienced in conveying materials, especially flocculent or cohesive materials, from a hopper or bin in a wide, shallow and uniform stream. It may be usefully applied in distributing a uniform layer of material on the surface of a sieve or screen.

I claim:

1. Apparatus for conveying pulverulent or broken material, which comprises a rigid member, a tray mounted alongside the rigid member in such a manner that the tray or a member attached thereto is normally held in, or nearly in, contact with the rigid member by the force of an elastic member, but is free to move against such force away from the position of contact, and means for imparting to the rigid member a reciprocating motion having a component parallel to the direction in which the material is to be conveyed, said arrangement enabling the momenta of the apparatus to be substantially equal to the momenta of the impact.

2. Apparatus as claimed in claim 1, wherein the tray and the direction of oscillation of the rigid members are substantially horizontal.

3. Apparatus as claimed in claim 1, wherein the tray is supported by a device which enables the inclination of the tray to be adjusted.

4. Apparatus as claimed in claim 1, wherein the tray is supported by and/or depends from rods to which the tray is pivotally attached and which are themselves pivotally mounted on fixed or adjustable bearings.

5. Apparatus as claimed in claim 1, wherein the member which is struck by the anvil is fixed to one or more of the said rods.

6. Apparatus for conveying pulverulent or broken material comprising a rigid member, a tray mounted alongside said rigid member in such a manner that the tray or a member attached thereto is normally held in, or nearly in, contact with the rigid member by the force of an elastic member, but is free to move against such force away from the position of contact, means for imparting to the rigid member a reciprocating motion having a component parallel to the direction in which the material is to be conveyed, said arrangement enabling the momenta of the apparatus to be substantially equal to the momenta of the impact, the delivery end of the tray having two portions, one on each side thereof, which are inclined downwardly therefrom, the lines at which the said portions meet the tray converging to a point at or near the forward edge of the tray.

7. Apparatus for conveying pulverulent or broken material, which comprises a rigid member, a tray mounted alongside the rigid member in such a manner that the tray or a member attached thereto is normally held substantially in contact with the rigid member by the force of an elastic member but is free to move against such force away from the position of contact, means for imparting to the rigid member a reciprocating

motion having a component parallel to the direction in which the material is to be conveyed, the tray and the direction of oscillation of the rigid member being substantially horizontal, and supporting means for said tray, said supporting means being pivotally mounted on bearings, said tray being pivotally attached to said supporting means.

8. In an apparatus for conveying pulverulent or broken material, a shallow, wide open tray, means for suspending said tray for substantially horizontal reciprocating motion, means independent of said tray and stationary and having a delivery mouth close to the bottom of the shallow tray for delivering the material to the tray while the tray moves therebeneath to distribute the material in a wide, shallow substantially uniform stream, an anvil also mounted to reciprocate longitudinally in parallelism with the tray and adjacent one end thereof, means for communicating horizontal reciprocation to said anvil, striker means movable back and forth substantially horizontally with said tray and positioned to be engaged and struck by said anvil and in turn to react and strike said anvil, both impact blows taking place in a substantially horizontal direction parallel with the motion of said tray, and yieldable means between said anvil and striker means for drawing same yieldably together.

9. An apparatus according to claim 8, further characterized by the fact that said striker means is carried by links pivoted to the tray and to a fixed support.

10. An apparatus according to claim 8, in which said yieldable means is in the form of coil springs, with means for adjusting the tension of said springs.

11. Apparatus according to claim 8, wherein struts are pivoted to an end portion of said tray and depend from the tray, means whereby the lower ends of said struts are pivoted to the apparatus frame, and means whereby said struts carry said striker means.

12. Apparatus according to claim 8, in which eccentric are mounted in substantially horizontal alignment with said anvil, and substantial horizontal links are pivoted between said anvil and said eccentric.

13. Apparatus according to claim 8, further characterized in that the tray converges toward a point at its delivery end with diagonal side edges, wings extending downwardly and forwardly from said diagonal edges on which the material is sprinkled in a wide shallow stream, and a deflecting plate forwardly of the forward edges of said wings.

GEORGE HARRY STRAIN.
